UNITED STATES PATENT OFFICE.

MAX BROWN, OF CHICAGO, ILLINOIS.

REVERSE CONTROL FOR MOTORS.

Application filed August 22, 1925. Serial No. 51,885.

My invention appertains generally to a motor reverse control, and more particularly to such a control for electric motors employed in connection with the operation of 5 elevators or lifts.

In this particular connection much difficulty has been encountered due to the carelessness of the operators who move the control lever from one extreme position rapidly 10 through the neutral position to the other extreme position, such quick movement of the lever causing a too rapid reversal of the electric motor and frequently causing serious damage thereto. A sudden reversal of the 15 direction of current in the motor armature by such rapid and uninterrupted movement of the control lever will blow out fuses; will stop the elevator between floors; will burn out the motor armature; and will cause arcing in switches and across the motor commutators, all of which, obviously necessitate expenditure for repairs and cause needless delay.

The main object of my invention, according 25 to which will prevent a rapid reversal of the motor, by causing the lever to come to a substantial rest in neutral position.

Another object is to provide a simplified 30 control box embodying a lever interrupting and retarding means for the purpose mentioned.

Still another object is to provide such an 35 interrupting and retarding means which may be cheaply manufactured and may be readily fitted to standard controls now in use.

Other advantages and objects will be apparent to those skilled in this art as the 40 description hereof progresses.

These objects are accomplished by the improved control means hereinafter described and which briefly embodies a control box including an independently movable operating handle carried on a lever pivotally mounted on the box, said lever carrying a 45 guide in the form of a roller member, the lever being movable to close contacts for operating a motor to raise or lower an elevator or lift. Mounted on the control box in the path of movement of the guide or roller, and in the neutral position of the lever, there is a guide plate embodying features for interrupting the continuous movement of the lever to retard it and prevent 50 rapid reversal of the motor.

In the accompanying sheet of drawings, to which reference should now be made, and wherein like parts are denoted by like reference characters,

Fig. 1 is a face plan view of a control box and lever showing the improved interrupting and retarding means in position;

Fig. 2 is a top plan view of the same mechanism;

Fig. 3 is a vertical sectional view through the control box and operating handle or lever and is taken along the line 3—3 of Fig. 1, looking in the direction of the arrows;

Fig. 4 is a perspective view of the retarding means or guide plate; and

Fig. 5 is a top plan view of said plate.

Looking to Figs. 1, 2 and 3, there is illustrated a conventional face member 10 of a control box of the type mentioned, said member being rounded in the usual way along its upper edge and centrally and pivotally carrying on a pivot 11, the usual lever 12 adapted to be swung either to the right or to the left as is common in this art. Integrally formed on the lever below its pivot is the customary segmental contact 13 engageable with the contacts 14 or 15 for closing the circuit with the motor to operate the lift in either an up or a 80 down direction.

The member 10 carries on its back side and centrally thereon at its top a plate 16 to which is bolted the improved retarding and guiding plate 17 of this invention, said 90 plate resting on the top side of the member 10, as shown. This guide member 17 is provided with a centrally disposed pocket 18 communicating with an offset passageway 19 arranged forwardly thereof and extending to the right as shown, said passageway being closed at one end and merging into a camming or guide face 20 at the opposite end where said passageway is open. Similarly, there is disposed rearwardly of the 100 pocket 18, an oppositely disposed passageway 21 also closed at one end and open at the other end, where there is another camming or guiding portion 22. The camming portions 20 and 22 are preferably rounded 105 at their upper edges as indicated generally at 23 in Fig. 4 so they better perform their guiding function as will presently appear. Centrally disposed in the pocket 18 there is arranged a pair of yieldable, spaced, stop members 24 for a purpose soon to appear.

The lever 12 carries in any suitable man-

ner, a forwardly projecting operating handle 25, centrally and axially bored out to receive a plunger 26 made fast on the lever 12 in a manner, by means of the spring 27, to 5 permit an independent or relative movement of the handle 25 with respect to said lever 12. The handle is provided with a roller 28 having a guide flange 29 so disposed that it may pass through the pocket 18 and passageways 19 and 21 in the guide plate 17. 10 A collar 30 holds the roller 28 in place.

In the operation of this control means, let us suppose the lever 12 is swung from the far left hand dotted position in Fig. 1 15 towards the right to reverse the motor and the direction of movement of the lift. The guide flange 29 and roller 28 move with the handle 25, the flange entering the passageway 21 and being guided thereinto by the cam face 22, the roller 28 and flange 29 having a rolling contact with the round edged cam face to reduce shocks. The handle 25, of course, has an independent movement due to the plunger and spring 20 construction shown. The handle will be interrupted in its continuous movement by the closed end of the passageway adjacent the pocket 18, and the operator to continue the movement must then pull the handle 25 outwardly across said pocket with the flange 29 furthermore being yieldingly retarded by the means 24, and into the passageway 19 and then through said passageway to 30 complete reversed position. The interruption and retardation by the offset passageways and yielding means 24 will be sufficient to bring the motor to rest to prevent its rapid reversal and thereby give assurance that carelessness will not cause damage to 35 the motor with its consequent costly delays. Furthermore, if it is desired to retain the lever in neutral position the flange 29 will be held locked yieldingly in such position against accidental displacement in all directions by the stop means 24 as shown in Fig. 40 45 3 and the ends of the pocket 18 as will be obvious. If it is desired to move the lever 12 from the extreme right hand position as viewed in Fig. 1, obviously the other cam face 20 comes into play to guide the roller 28 and flange 29 properly.

It will thus be seen that there is herein provided apparatus in which the several ob-

jects of this invention are achieved, and that the same is of simple construction, yet dependable in operation, and is well adapted to meet the exacting conditions of hard practical use. 55

While I have shown the preferred form of the invention, it is to be understood that the same may be useful in other connections, and that various changes in form, construction and arrangement of parts may be resorted to without departing from the spirit and scope of this invention as hereinafter claimed. 60 65

What I claim is:

1. In a reverse control for motors, the combination with the control box and lever, of an independently movable operating handle carried by the lever, and a guide plate disposed on the box including means for interrupting the continuous movement of the lever and yieldingly locking it in neutral position against accidental displacement in all directions. 70 75

2. In a reverse control for motors, the combination with the control box and lever, of an independently movable operating handle for the lever, a guide plate having offset, oppositely disposed passageways for interrupting continuous movement of the lever through its neutral position, and yielding means arranged between the passageways for further retarding continuous movement of the lever. 80 85

3. In a guide member of the character described, the combination of a plate having a central pocket, passageways on opposite sides of the pocket and communicating therewith, said passageways leading in opposite directions from the pocket, and yieldable stops arranged in the pocket. 90

4. In a guide member of the character described, the combination of a plate having a central pocket, passageways on opposite sides of the pocket and communicating therewith, said passageways leading in opposite directions from the pocket and having their entrances provided with camming surfaces, and spaced yieldable stops mounted in the pocket. 95 100

Signed at Chicago, in the county of Cook, and State of Illinois, this 18th day of August, 1925.

MAX BROWN.
